[57] CLAIM

The ornamental design for a mini-bowling game, as shown and described.

DESCRIPTION

FIG. 1 is a perspective view taken from the top, front and right side of a mini-bowling game showing my new design;

FIG. 2 is a top plan view thereof;

FIG. 3 is a right side elevational view thereof, the left side being a mirror image of the right side shown;

FIG. 4 is an enlarged front elevational view thereof, and

FIG. 5 is an enlarged rear elevational view thereof.

The broken line representation of bowling pins in FIGS. 1, 2 and 4 are for purposes of illustration only and form no part of the claimed design.

FIG. 1.

FIG. 2.

FIG. 3.

FIG. 4.

FIG. 5.
